CONTAINER AND METHOD OF MAKING
SAME

Isadore H. Weber, Philadelphia, Pa., assignor to
David Weber & Co., Philadelphia, Pa., a corpo-
ration of Pennsylvania

Application December 6, 1935, Serial No. 53,244

4 Claims. (Cl. 93—45)

This invention relates to new and useful im-
provements in container bodies and methods of
making the same and more particularly to cor-
rugated containers such as boxes, cartons and
5 the like having a plurality of wall thicknesses.

The principal object of the present invention
is to provide a novel container body of the char-
acter set forth having a plurality of wall thick-
nesses constructed and arranged to provide an
10 offset shoulder construction for the reception and
seating of a cover or closure member.

Another object of the present invention is to
provide a novel method for making containers of
the character set forth wherein machining or
15 otherwise cutting away a portion of one wall sec-
tion to produce an offset shoulder construction
is entirely eliminated.

A further object of the invention is to pro-
vide a novel method for making containers of
20 the stated character having an off-set shoulder
construction adjacent one or both ends of said
containers either internally or externally thereof.

A still further object of the present invention
is to provide a novel method for making con-
25 tainers of the character stated which renders
manufacture of the same comparatively simple
and inexpensive.

Other objects of the invention and the fea-
tures and details of construction thereof are set
30 forth hereinafter and shown in the accompan-
ying drawings, in which:

Fig. 1 is a fragmentary view in perspective il-
lustrating certain steps of the invention.

Fig. 2 is an enlarged view in perspective of a
35 container blank.

Fig. 3 is a view in perspective of one form of
container.

Fig. 4 is a view in perspective of a cover or
closure member for the container of Fig. 3, a
40 portion thereof having been cut away to illus-
trate the same.

Fig. 5 is a view similar to the disclosure in
Fig. 2 showing another form of container blank.

Fig. 6 is a view similar to the disclosure in
45 Fig. 3 showing another form of container.

Fig. 7 is a view in perspective of a cover or
closure member for the container disclosed in
Fig. 6.

Fig. 8 is a fragmentary view in perspective
50 showing a modification of the disclosure in Fig. 1.

Fig. 9 is an enlarged view in perspective of a
container blank made in accordance with the
modification of the invention disclosed in Fig. 8, a
55 portion of said blank having been cut away to

better illustrate certain structural features of
the same.

Fig. 10 is a view in perspective of still another
form of container.

Fig. 11 is a view in perspective of a cover or
closure member for the container illustrated in
Fig. 10.

Fig. 12 is a view similar to the disclosure in
Fig. 9 showing another form of container blank.

Fig. 13 is a fragmentary view in perspective
of still another container; and

Fig. 14 is a view in perspective of a cover or
closure member for the container of Fig. 13.

Referring now to the drawings, the invention
contemplates in general the formation of a con-
tinuous composite run of board having a plu-
rality of corrugated wall thicknesses wherein one
wall thickness is of less width than other wall
thicknesses thereof, as for example, in the man-
ner shown in Fig. 1 of the drawings wherein a

continuous run of single-faced transversely cor-
rugated board A is fed by means of a roll 1 into
parallel contact with the adjacent liner or fac-
ing of a continuous run of double-faced trans-
versely corrugated board B passing intermediate

5 said roll 1 and another roll 2 disposed in oppo-
sition thereto. The single-faced run A is fed into
contact with the double-faced run B so that the
exposed ridges of the corrugations of the former
contact the facing or liner of the latter, said

10 runs A and B being secured together to form
a continuous composite double-walled run C by
means of adhesive previously applied to the ridges
of said corrugations of the run A from a paste

15 box 3 by rolls 4. The composite run C passes
intermediate a series of rolls 5 and steam plates
or other suitable heating elements 6 where the
same is dried and thereafter passes intermediate

20 rolls 7 and 8, one of which is provided with an
adjustable cut-off element 9 operable to sever sec-
tions or blanks D from said composite run C at
predetermined intervals transversely thereof.

25 While the foregoing description and illustra-
tion relates particularly to the manufacture of
container blanks having a plurality of corrugat-
ed wall thicknesses wherein the axes of the cor-
rugations of each are substantially parallel, said

30 invention is equally adaptable to the manufacture
of container blanks having a plurality of cor-
rugated wall thicknesses wherein the axes of the
corrugations of each are disposed substantially

35 at right-angles to the axes of the corrugations
of adjacent wall thicknesses in accordance with
any one of the several methods of making corru-

40 gated board disclosed in U. S. Letters Patent No.

55

2,008,974 dated July 23, 1935, as well as my co-pending application for U. S. Letters Patent bearing Serial No. 46,171, filed October 22, 1935 and the co-pending application for U. S. Letters Patent of David Weber bearing Serial No. 46,389, filed October 23, 1935.

One such method of making corrugated board of the above character is diagrammatically shown in part in Fig. 8 of the drawings hereof, wherein 10 pre-formed single-faced sheets of corrugated board B' are successively fed in abutting relation by continuously moving dogs 10 into parallel contact with a continuously fed independent run of liner or facing sheet 11. The facing sheet 11 is 15 fed so that the same contacts the exposed ridges of the corrugations of said pre-formed sheets B' and is secured thereto to form a substantially continuous double-faced run E by means of adhesive previously applied to said corrugations 20 from a paste box 12 by rolls 13. In this ramifications of the invention the axes of the corrugations of the pre-formed sheets B' extend in the direction of feed thereof and substantially at right-angles to the axes of the corrugations of the 25 continuous run of single-faced transversely corrugated board A which is fed by a roll 14 into parallel contact with the liner or facing 11 of the previously described composite double-faced run E passing intermediate said roll 14 and a roll 15 30 disposed in opposition thereto. As shown the exposed ridges of the corrugations of the single-faced run A contact the facing or liner 11 of the run E and the same is secured thereto by means of adhesive previously applied to said corrugations 35 from the paste box 3 by rolls 4 to form a continuous composite double-walled run C', the axes of the corrugations of adjacent wall thicknesses of which are disposed substantially at right-angles to each other. 40

The composite run C' then passes intermediate the rolls 5 and steam plates or other suitable heating elements 6, where the same is dried and thereafter passes intermediate the rolls 7 and 8, one of which carries the adjustable cut-off element 45 9 operable to cut sections or blanks D' from said composite run C' at predetermined intervals transversely thereof.

In the foregoing descriptions, it is to be particularly observed that in each instance one particular wall thickness is of greater width than others so that the latter project a predetermined distance beyond at least one side edge of the former as shown, and therefore the container blanks D and D' severed from the composite runs C and C' respectively will likewise comprise a plurality of wall thicknesses wherein one of said thicknesses is of less width than others as disclosed in Figs. 2 and 9 of the drawings. However, it is pointed out that the invention may be practiced with equal effectiveness by reversing the relative dimensions of said wall thicknesses so that the present narrower wall thickness is of greater width than others. Furthermore, in certain instances it may be desirable to form container blanks wherein one wall thickness projects beyond two opposite side edges of the other wall thicknesses thereof as shown in Figs. 5 and 12 of the drawings, and container blanks of this particular character, designated generally as F and F' respectively, may be formed in the manner disclosed in Figs. 1 and 8 by forming wall thicknesses having predetermined relative widths and positioning the same transversely with respect to

each other so that their longitudinal axes lie in substantially the same vertical plane.

As will be observed from the foregoing description as well as the drawings, the blanks D' and F' embody substantially the same structural features present in the blanks D and F, the only essential difference being that in the former the axes of the corrugations of adjacent wall thicknesses extend substantially at right-angles to each other as shown in Figs. 9 and 12 of the drawings, whereas in the latter the axes of the corrugations are substantially parallel as shown in Figs. 2 and 5 thereof.

After the container blanks have been severed from the composite runs in the manner previously described, the same are scored transversely thereof parallel to their end edges 16 at predetermined spaced intervals depending upon whether a container having a corner or side wall seam is desired, and, for example, in the former instance the blanks are scored transversely at equally spaced intervals with respect to each other and the transverse end edges 16 thereof as indicated at 17 in Figs. 2 and 9 of the drawings so that the line of abutment of said end edges will reside at a corner of a container, and in the latter instance the blanks are similarly scored transversely at predetermined spaced intervals as indicated at 18 in Figs. 5 and 12 so that the line of abutment of the opposite end edges 16 will reside in a side wall portion of a container body.

The container bodies are formed by bending the blanks previously described along their several transverse scores 17 and 18 respectively, to place the opposite end edges 16 of each in substantially abutting relation as shown in Figs. 3, 6, 10, and 13 of the drawings, said end edges being secured in the aforementioned abutting relation by any suitable means such as an adhesive strip or the like 19. The container bodies may be formed so that the narrower wall thicknesses are disposed externally or internally of the wall thicknesses of greater width as may be desired, and in the former instance disposition of said narrower wall thickness externally of the other wall thicknesses, produces a shoulder 20 on the exterior of said container body which terminates at its inner edges in a projecting sleeve portion 21 formed by the inner wall thickness. Similarly, formation of a container body with the narrower wall thickness disposed internally of the other produces a shoulder 22 in the interior of said container body which terminates at its outer edges in a projecting sleeve portion 23 formed by the outer wall thickness.

In the present instance the projecting sleeve portions 21 of the container bodies shown in Figs. 3 and 10 of the drawings are arranged to receive closure members 24 which overlie the same in abutting relation with respect to the external shoulders 20 thereon, and the projecting sleeve portion 23 of container bodies illustrated in Figs. 6 and 13 are arranged to receive similar closure members 25 which are inserted inwardly of said sleeve portions 23 in the manner shown in either Figs. 7 or 14 in abutting relation with respect to the internal shoulders 22.

While the invention has been illustrated and described in connection with corrugated or like container bodies of tubular form and open at the ends, it will be obvious that the novel shoulder and projecting sleeve construction herein disclosed and forming the subject of the present invention may be embodied in the manufacture

of still other types of containers or container bodies whether of the tubular, open-ended form shown, or provided with integral inclosure flaps at one end thereof, of the general character disclosed in my co-pending application for Letters Patent of the United States bearing Serial No. 53,666, filed December 9, 1935.

The present invention provides a novel method of manufacturing corrugated board container bodies which are of an extremely rugged and substantially indestructible nature embodying certain novel structural features for cooperation with suitably formed cover or closure members to provide a tight, substantially sift-proof container, and while certain specific embodiments and structural details of the invention have been illustrated and described for descriptive purposes, it is not intended that the same be precisely limited thereto but that changes and modifications may be incorporated within the scope of the annexed claims.

I claim:

1. The method of making container bodies, consisting of forming a continuous run of composite board having a plurality of corrugated wall thicknesses wherein one wall thickness is of less width than others and secured to the latter throughout its entire width, cutting sections of board from said composite run at predetermined intervals transversely thereof to form container blanks having one wall thickness of less width than others which project a predetermined distance beyond one side edge of the former, scoring said blanks at predetermined intervals transversely thereof, and forming container bodies from the blanks by bending the same along the several scores therein so that the opposite end edges thereof abut and the respective wall thicknesses cooperate to form a shoulder and projecting sleeve portion adjacent at least one end of said bodies.

2. The method of making container bodies, consisting of forming a continuous run of composite board having a plurality of corrugated wall thicknesses wherein one wall thickness is of less width than others and secured to the latter throughout its entire width, cutting sections of board from said composite run at predetermined intervals transversely thereof to form container blanks having one wall thickness of less width than others which project a predetermined distance beyond one side edge of the former, scoring said blanks at predetermined intervals trans-

versely thereof, forming container bodies from the blanks by bending the same along the several scores therein so that the opposite end edges thereof abut and the respective wall thicknesses cooperate to form a shoulder and projecting sleeve portion adjacent at least one end of said bodies, and thereafter securing said opposite end edges in said abutting relation. 5

3. The method of making container bodies, consisting of forming a continuous run of composite board having a plurality of corrugated wall thicknesses wherein one wall thickness is of less width than others which project a predetermined distance beyond the opposite side edges of the former which is secured to said other wall thicknesses throughout its entire width, cutting sections of board from said composite run at predetermined intervals transversely thereof to form container blanks having certain wall thicknesses projecting a predetermined distance beyond the opposite side edges of at least one wall thickness thereof, scoring said blanks at predetermined intervals transversely thereof, and forming container bodies from the blanks by bending the same along the several scores therein so that the opposite end edges thereof abut and the respective wall thicknesses cooperate to form a shoulder and projecting sleeve portion adjacent each end of said bodies. 10 15 20 25

4. The method of making container bodies, consisting of forming a continuous run of composite board having a plurality of corrugated wall thicknesses wherein one wall thickness is of less width than others which project a predetermined distance beyond the opposite side edges of the former which is secured to said other wall thicknesses throughout its entire width, cutting sections of board from said composite run at predetermined intervals transversely thereof to form container blanks having certain wall thicknesses projecting a predetermined distance beyond the opposite side edges of at least one wall thickness thereof, scoring said blanks at predetermined intervals transversely thereof, forming container bodies from the blanks by bending the same along the several scores therein so that the opposite end edges thereof abut and the respective wall thicknesses cooperate to form a shoulder and projecting sleeve portion adjacent each end of said bodies, and thereafter securing the opposite end edges in said abutting relation. 30 35 40 45 50

ISADORE H. WEBER.
